UNITED STATES PATENT OFFICE

2,501,938

MACHINE FOR MANUFACTURING SPI-
RALLY WOUND STRAWS OR TUBESAlbert Aba Heyman, Baltimore, Md., assignor to
Joseph Shapiro, Baltimore, Md.

Application January 24, 1947, Serial No. 723,985

6 Claims. (Cl. 93—80)

1

My invention, which relates principally to machines for making spirally wound straws from paper strips, has for its objects:

1. To improve the machine disclosed in United States Letters Patent No. 1,911,298, issued May 30, 1933, and No. 1,967,171, issued July 17, 1934;
2. To provide an improved belt tensioning device, so as always to maintain a substantially constant tension on the belt regardless of its stretch;
3. To provide an improved tube-cutting mechanism;
4. To provide means whereby the lengths of straws cut off can be instantly and conveniently changed as desired by the attendant, thereby making it possible to cut straws of various desired lengths without stopping the machine; in consequence of which the wastage due to trimming is reduced to an almost negligible amount;
5. In general, to improve previous machines so as to reduce manufacturing costs and maintenance, and increase the efficiency of the machines.

Other objects will in part be obvious and in part will appear from the following description.

To the attainment of the aforesaid objects and ends, invention further resides in the novel details of construction, combinations and arrangements of parts, all of which will first be described and then be specifically pointed out in the appended claims, reference being had to the accompanying drawings, in which:

Fig. 1 is a top plan view of a machine embodying my invention, the glueing unit being omitted.

Fig. 2 is a side elevation of the same.

Fig. 3 is an enlarged detail elevation of the adjustable belt pulley unit, looking in the direction of the arrow *a* in Fig. 1.

Fig. 4 is a section on the line 4—4 of Fig. 3.

Fig. 5 is a detail section on the line 5—5 of Fig. 3.

Fig. 6 is a detail elevation of the cutting mechanism, looking from left to right in Figs. 1 and 2.

Fig. 7 is an enlarged detail of the speed adjusting pulley of the cutting mechanism.

Fig. 8 is a detail elevation of a modification.

Fig. 9 is an enlarged detail view of the driving pulley for the belt speed adjustment.

Fig. 10 is an enlarged detail end view of the arm and knife blade, a portion of the final straw guide being shown in dotted lines.

In the drawings, in which like numerals and letters of reference indicate like parts in all the figures, 1 represents the bed of the machine which is supported on a frame composed of upper

horizontal angles 3, lower horizontal angles 4, and legs 2.

Secured in a fixed position on the bed 1 is a cross-head 5 at one end of which is welded a vertical plate 6 to which a shaft bearing 7 is secured.

A gear box 8 is mounted on legs 2, 2^a and has bearings 9 for a counter shaft 10 on which is a V-type pulley 11, later again referred to. A bearing 13 on the box 8 assists bearing 7 in supporting the driving shaft 12 of the stationarily located belt pulley 14. The shafts 10 and 12 are connected by bevel gears 11.

Referring particularly to Figs. 3, 4 and 5, it will be seen that 15 indicates a sliding carriage having a T-head 16 in the form of a plate which slides on ways 17 welded to the sides of the inverted U-shaped cross head 5. The carriage includes pairs of bearing lugs 18 which carry rock shafts 19 on which parallel links 23 are pivoted. The carriage 15 also includes a lug 44 having a bearing for an adjusting screw 45 that is threaded into a lug 47 on the cross head 5 and is swivelly connected with the lug 44 as at 46.

The links 23 are secured to rock shafts 22 journalled in the bearing lugs 21 of a pulley carriage 20. The carriage 20 has a bored boss 24 to the lower end of which is secured a tapped plate 25 into which the threaded end 30 of the pulley spindle 26 is threaded (see Fig. 5). The spindle 26 has two spaced enlargements 27, 28 to fit the bore of the boss 24 in which the spindle is held vertically adjustable by the screw connection 30 with plate 25 and by a set screw 29. The

second belt pulley 31 is journalled on the spindle 26 on a ball bearing 36 and is held in place between the enlargement 27 and a cap 32 that is secured to the end of the spindle 26 by a screw 35 and is held from turning on the spindle by a pin or pins 34. The cap has recesses 33 to receive a rod by means of which, when set screw 29 is released, the spindle may be turned to adjust it (and consequently the pulley 31) up or down.

45 A sprocket chain 38 has one of its ends welded or otherwise suitably secured to a lug 37 on the carriage 20. The chain passes over a sprocket 39 on a shaft 40 journalled in a bracket 41 that is welded on the cross-head 5. The chain passes down through a slot 42 in the top of the cross-head 5 and carries a weight 48. An adjustable stop 43 is threaded into bracket 41 to be engaged by the carriage 20, should the belt break.

The gear box 8 has an extension with a bearing 49 for the drive shaft 50 for the glue-applying

mechanism (not shown). The shaft 50 is driven via a sprocket and chain connection 112 with shaft 10. See dotted lines, Fig. 1.

The mandrel 52 is mounted on a bracket 51 and may be of the usual construction. The glue-applying mechanism may be substantially the same as that disclosed in Pat. No. 1,967,171 aforesaid.

The usual belt 53 is passed about the pulleys 14 and 31, one flight being twisted around the mandrel. The usual intermediate straw guides 54 are provided. The end guide 55, however, has an elongated tubular shank 56 adjustably held by set screw 60 in the support 59 and having its outer end provided with a flat edge 58 and a tapered portion 57 adjacent thereto. (See Figs. 1 and 2.)

A bearing bracket 61 is secured to the base 1 and carries a crank shaft 62 on which is a disc 63 having a wrist pin 64 to which one end of an arm 68 is pivoted. The arm is slotted and a bolt 66 passes through a slide block 67, through the slot in the arm and into an extension 65 of the bracket 61 to constitute a shifting pivot for the arm 68. The arm 68 carries a knife blade 69 removably held in place by a suitable clamp 70. The knife blade 69 is of generally triangular cross section and is held with the flat side of the blade canted at an approximate angle of 25 degrees to the outer vertical edge 58 of the guide 55 in order to permit the continuous straw to advance without interference by the knife blade 69.

The mechanism for driving the belt pulley 14 is best shown in Figs. 1 and 2, by reference to which it will be seen that a V-pulley 71 is secured on shaft 10, over which pulley an endless V-belt 72 passes. The belt 72 also passes about a two-part V-pulleys 75, 76 on the shaft 74 of a motor 73. One part 75 of the two-part pulley is fixed on the shaft, while the other part 76 is continuously pushed toward the part 75 by a suitable spring 77^a in a spring box 77, fast on shaft 74. (See Fig. 9.)

The motor 73 is mounted on a base plate 78 having, at one end, lugs 79 for cooperation with lugs 80^a on a cross bar 80, and shaft 81 as a hinge joint. Other lugs 82 on the other end of plate 78 have bearing holes for the trunnion shaft 84 of a block 83. The block 83 is bored and tapped to receive a screw shaft 89. The screw has a swivel connection with another block 87 whose trunnion shaft 88 is mounted in lugs 86 on a plate 85 secured to a suitable standard 85. The screw shaft 89 is connected to an adjusting shaft 91 by a universal joint 90. The shaft 91 passes through a bearing hole in the bed 1 and carries a crank disc 92 which is provided with a suitable combined spring-plunger-latch and handle 93. The bed 1 has a suitably located recess 94, or recesses, for the end of the spring latch to enter and hold the disc 92 from accidentally turning.

By turning the disc 92, shaft 91 and screw-shaft 89 may be turned in either direction to raise or lower the motor 73 toward or from pulley 71 and thereby decrease or increase the speed of pulley 71, and consequently that of the belt pulley 14, and also of the glue-applying apparatus driving shaft 62. The operation of adjusting shaft 91 serves, by increasing or decreasing the speed of the winding belt 53, the cut-off mechanism's speed being unchanged, to provide for the cutting of longer or shorter straws from the continuous tube.

The same effect may be accomplished by changing the speed of the cutting mechanism and

letting the forming mechanism run at a fixed speed, as will presently more fully appear.

The mechanism for driving the cutter or knife will now be explained, reference being made to Figs. 1, 2 and 6 of the drawings.

A platform 100 is adjustably suspended by slotted arms 101 secured by cap screws 104 to arms 102 depending from a plate 103 that is welded to the bed 1; a suitable motor 105 is mounted on the platform. On the motor shaft 106 is a two-part V-type pulley, one part 107 of which is fast on the motor shaft, while the other part 109 is threaded on the threaded portion 108 of the motor shaft and is adjustably held by a set screw 10.

A gear box 95 is mounted on the plate 103 and has a driving shaft 96 suitably geared to a driven shaft 97. The shaft 96 has a V-type pulley 99. A V-belt 111 passes about the pulleys 99 and 107, 109.

By raising or lowering the motor platform and adjusting pulley section 109 toward or from section 107, the speed at which shaft 96 is driven may be varied as desired.

The shaft 62 hereinbefore mentioned is connected to shaft 97 by a flexible coupling 98. Thus the shaft 97 turns shaft 62 at the same speed.

In lieu of the adjustable pulley arrangement shown in Fig. 7, a pulley 15^a similar to that 75, 76, etc. shown in Fig. 9 may be used on shaft 106 in which event a belt tightener 113 may be used and controlled by a screw 114 swivelly connected at 115 to the belt tightener and threaded through a suitable bracket 116. When the belt tightener (shown in Fig. 8) is used the cap screws 104 may be left tight and no frame adjustments need be made.

It is essential that the pulleys 14 and 31 line up properly with the horizontal plane of the mandrel. The construction shown in Figs. 3 to 5 inclusive enables this alignment to be maintained at all times. After placing a belt around the pulleys 14 and 31 and winding it about the mandrel, screw 43 is backed off to clear the carriage 20. Should the arms 23 be found out of vertical, they are brought to the vertical by adjusting screw 45. The weight 48 exerts a constant tension on the belt. If pulley 31 is too high or too low when arms 23 are vertical, spindle 26 is lowered or raised accordingly by turning the spindle after which the spindle is again locked with the set screw 29.

Attention is called to the way in which the knife blade 69 moves. It is travelling faster on its down-stroke than on its up-stroke and imparts a combined draw-cut-and-chop action on the straw to sever it.

The motors 73 and 105 are run at fixed or predetermined speeds which are not changed in order to adjust the machine to make straws of different lengths; therefore the machine may always be run to deliver its maximum output.

From the foregoing description, taken in connection with the accompanying drawings, it is thought that the construction, operation and advantages of my invention will be clear to those skilled in the art.

What I claim is:

1. In a spirally-wound-tube-making machine 70 wherein is provided a support on which are mounted a horizontally disposed pair of belt pulleys and a belt passed around the pulleys the improvement which comprises a stationary support for one of said belt pulleys, an adjustable 75 sliding carriage mounted on said support, means

for adjusting said carriage toward or from said stationary support, a pulley carriage for the other belt pulley, parallel links connecting said carriages together, and means continuously tending to move said pulley carriage in a direction away from said stationary support, thereby to maintain a uniform tension on the spinning belt.

2. In a spirally-wound-tube-making machine wherein is provided a support on which are mounted a horizontally disposed pair of belt pulleys and a belt passed around the pulleys the improvement which comprises a stationary support for one of said belt pulleys, an adjustable 10 slidable carriage mounted on said support, means for adjusting said carriage toward or from said stationary support, a pulley carriage for the other belt pulley, parallel links connecting said carriages together, means continuously tending to move said pulley carriage in a direction away from said stationary support, thereby to maintain a uniform tension on the spinning belt, and means for mounting said other belt pulley on said pulley carriage, said last-named means including a spindle vertically adjustably held in said pulley carriage and on which spindle said other belt pulley is journaled, and means by which said spindle may be moved axially for adjustment purposes, and means to hold said spindle in its adjusted positions against accidental displacement.

3. In a spirally-wound-tube-making machine wherein an endless belt passes over two separated belt pulleys mounted on a support and means is provided for continuously tending to separate said pulleys to effect a constant tension on said belt, the improvement which comprises a slidable carriage mounted on said support for movement in a direction from one pulley toward the other, means for effecting adjusting movement of said carriage, a pulley carriage for one of said pulleys vertically spaced from said slidable carriage, parallel links connecting said carriages together, and means continuously tending to move said pulley carriage in a direction to apply tension to said belt.

4. In a spirally-wound-tube-making machine wherein an endless belt passes over two separated belt pulleys mounted on a support and means is provided for continuously tending to separate said pulleys to effect a constant tension on said belt, the improvement which comprises a slidable carriage mounted on said support for movement in a direction from one pulley toward the other, means for effecting adjusting movement of said carriage, a pulley carriage for one of said pulleys vertically spaced from said slidable carriage, parallel links connecting said carriages together, means continuously tending to move said pulley carriage in a direction to apply tension to said belt, and a back-stop mounted on said support for engagement by said pulley carriage when no continuous belt is on said pulleys.

5. In a spirally-wound-tube-making machine wherein an endless belt passes over two separated belt pulleys mounted on a support and means is provided for continuously tending to separate said pulleys to effect a constant ten-

sion on said belt, the improvement which comprises a slidable carriage mounted on said support for movement in a direction from one pulley toward the other, means for effecting adjusting movement of said carriage, a pulley carriage for one of said pulleys vertically spaced from said slidable carriage, parallel links connecting said carriages together, means continuously tending to move said pulley carriage in a direction to apply tension to said belt, said pulley carriage having a bore, a spindle mounted in said bore, a threaded element carried by said pulley carriage, said spindle having a threaded portion cooperating with said threaded element for adjusting said spindle axially in said bore, said one of said pulleys being journaled on said spindle, and means on the outer end of said spindle by which it may be turned for adjustment and means to hold said spindle in its adjusted positions against accidental displacement.

6. In a spirally-wound-tube-making machine wherein an endless belt passes over two separated belt pulleys mounted on a support and means is provided for continuously tending to separate said pulleys to effect a constant tension on said belt, the improvement which comprises a slidable carriage mounted on said support for movement in a direction from one pulley toward the other, means for effecting adjusting movement of said carriage, a pulley carriage for one of said pulleys vertically spaced from said slidable carriage, parallel links connecting said carriages together, means continuously tending to move said pulley carriage in a direction to apply tension to said belt, said pulley carriage having a bore, a spindle mounted in said bore, a threaded element carried by said pulley carriage, said spindle having a threaded portion cooperating with said threaded element for adjusting said spindle axially in said bore, said one of said pulleys being journaled on said spindle, means on the outer end of said spindle by which it may be turned for adjustment and means to hold said spindle in its adjusted positions against accidental displacement, and a back-stop mounted on said support for engagement by said pulley carriage when no continuous belt is on said pulleys.

ALBERT ABA HEYMAN.
